UNITED STATES PATENT OFFICE.

JACOB FRANZMANN, OF CINCINNATI, OHIO, ASSIGNOR OF ONE-HALF TO
HENRY VARWIG, OF SAME PLACE.

MACHINE FOR SHAPING WOODEN SHOVELS.

SPECIFICATION forming part of Letters Patent No. 235,352, dated December 14, 1880.

Application filed May 19, 1880. (No model.)

To all whom it may concern:

Be it known that I, JACOB FRANZMANN, of the city of Cincinnati, county of Hamilton, State of Ohio, have invented a new and useful Improvement in Machines for Shaping Wooden Shovels, of which the following is a specification.

The object of my invention is to clamp the blanks from which the blades of malt-shovels are to be formed, guide and feed them to a revolving cutting-tool to give them the proper shape.

The invention will be first fully described in connection with the accompanying drawings, and then particularly pointed out in the claims.

In the accompanying drawings, in which similar letters of reference indicate identical parts throughout the various views, Figure 1 is a top-plan view of a machine embodying my invention with the bed-plate and feeding device in position to commence the operation of dressing the front of the shovel. Fig. 2 is a transverse vertical section thereof, and Fig. 3 is an inverted plan view of the bed-plate. Fig. 4 is a top-plan view of the machine when adapted to dress the back of the shovel-blade, a portion of the bed-plate being broken away to expose the device for feeding the plate forward under the revolving cutter. Fig. 5 is a transverse vertical section of the same. Fig. 5^a is a similar section looking in the opposite direction, and Fig. 6 is a side elevation of the slotted guide which prevents the follower from turning when the feed-screw is revolved. Fig. 7 is a perspective section view of the front of the shovel, and Fig. 8 a plan elevation of the shovel-back.

The machine as adapted to forming the concave front of the shovel, as represented in Figs. 1, 2, and 3, will be first described.

The frame-work of the machine is represented by A. A portion of the frame overhangs a bed-plate, B, upon which the shovel-blank is to be secured, and in this overhanging part is mounted a revolving cutter-head, upon which are secured cutter-blades C. The edges of the blades are curved the reverse shape of the front of the shovel. The bed-plate has a central hub, a, and a flange, b', concentric with it, projecting down from its

under side. These are planed off true upon their lower edges and rest upon the plate or carriage D. The top of plate D is also planed off true to permit the plate B to turn upon it around a journal-pin, b², which passes through the hub and carriage D. The head of the pin is countersunk into the upper surface of the bed-plate, and the part that passes through plate D is turned smaller, so that the nut on the under side may be tightened up without causing the plates to bind. The movement of plate B is limited by pins in its under side entering curved slots in plate D, as shown in dotted line, Fig. 3.

The carriage D, when in the forward position, (shown clearly in Fig. 2,) rests upon a frame, E. This frame is fitted to slide vertically, and to be elevated by a treadle, F, to bring the top of the frame up even with slides G, of which there are two, one upon each side of the frame. The movement of the frame upward is limited by stops A', which are secured on top of the frame to overhang the plate D. The weight of the frame and the bed-plate and carriage is nearly counterbalanced by the weighted lever H.

The carriage-plate D has a lug or boss, d, upon its under side, which is tapped to receive the feed-screw I. The shaft of the screw has collars i i upon each side of a slotted angle-piece, I', secured upon the front cross-brace of frame A.

Upon the rear edge of the bed-plate B are two dogs, b³, against which one edge of the shovel-blank is placed; the lower end is pushed against the toothed dog b⁴, and the blank firmly clamped in place by the hand-screws b⁵.

The shovel-blank (which is wider at the bottom than at the top) being secured upon the bed-plate, and the machine in the position shown in Figs. 1 and 2 just ready to start, the operator takes hold of the shovel-handle and turns the plate until the forward edge of the blank is about parallel with the cutter-shaft. Now, by placing his foot upon the treadle and elevating the bed-plate and carriage the blank is brought under the action of the cutters C. By turning the hand-wheel with his left hand the carriage is advanced by screw I under the revolving cutter, while the

bed-plate and blank are turned as the carriage advances until, when the rear edge of the blank is reached, it is in turn nearly parallel with the cutter-shaft. Thus the operator, with one hand upon the feed-wheel and the other upon the shovel-handle, has perfect control of the feed, and the shovel is dished out to the proper shape, while the surrounding edges are left up sharp, and no accident is liable to occur should the grain of the wood be uneven or some blanks harder than others.

For dressing different-sized shovels, the dogs b^3 and b^4 are adjustable nearer to or farther from the center of the bed-plate. Some shovels are dished out, leaving an arch-shaped edge around the top, while others are dished out each side of the handle, leaving more wood in front of the handle for strength. To finish the first kind the blank is gradually turned as it is fed forward, so that when the center is reached the axes of the cutter-head and shovel-handle are parallel. To finish the second kind the blank is fed forward without turning until the cutter reaches the opposite edge. The blank is then turned until it is dressed up to the edge.

To finish the backs of shovels the bed-plate B and carriage D are removed and replaced by the bed-plate and guides represented in Figs. 4, 5, and 6. The cutters C are also replaced by the concave-edged cutters C'.

The machine as changed will now be described.

J is the carriage, upon which the partially-formed blade is secured.

Upon each side of the machine are curved guides K K'. These arch across the machine-frame, and are secured upon the front and rear cross-bars. They are curved upon their inner faces, as well as upon top, the curve in K being concave and the curve in K' convex. Both curves are concentric, to guide the carriage J in a circular path as it is fed forward under the revolving cutter.

L is a slotted guide secured to the under side of the carriage. Upon the side of the plate that receives the lower end of the shovel-blade the curve of the slot in guide L is concentric with the upper curve of the guide K, and its side curve also fits the curve in the side of guide K. From the inner face of K, and near the vertical center of its arch, a pin projects into the slot in guide L, as seen in Fig. 5.

The guide K' is provided with a curved slot similar to the slot in L, which extends nearly the whole length of the guide underneath the bed-plate J. Upon this side of the plate two lugs project down, one near the forward and one near the rear edge of the plate. Pins projecting horizontally from these lugs enter the curved slot in guide K'. These pins, as well as the one entering guide L, are armed with rollers to reduce friction.

M is a feed-screw. It has its bearings upon the front and rear cross-brace of the frame,

and has collars upon each side of its front bearing to prevent end motion.

N is the nut or follower, which, as it is carried back and forth by revolving screw M, imparts motion to the carriage J through a slotted lug, O, which projects down from the under side of the carriage, and a pin, n, which projects from the side of the follower N and enters the slot in lug O. A pin, n', projects from the opposite side of the follower into a slot in a guide, P, which extends across the frame of the machine. Its purpose is to prevent the nut from turning when the feed-screw is revolved. The pin n fits its slot loosely, so as to permit the plate J to turn and have vertical play without binding as it is fed forward by the screw.

The top of the edges surrounding the dished front of the shovel are in the same plane, which is parallel to the axis of the shovel-handle, while the back of the shovel curves from near the middle of the back toward the front lower edge.

In order to make the blade of nearly uniform thickness, the transverse curve near its top must gradually spread until, at the bottom of the blade, it is much flatter. This result is accomplished and the incline given to the back of the shovel by the central bearing or guide-pin upon one side and the two pins at opposite sides of the plate upon the other. On the side of the machine nearest the handle, the guide-pins being nearly below the opposite edges of the shovel, the leading one will reach the top of the curve about the time the cutter begins to act upon the blade. As the carriage is fed forward this end gradually assumes a lower position until the center of the blade is beneath the cutter, while the opposite end at the same time has been carried up by its pin, which has reached the center of the arch in guide L. This gives the back, at its longitudinal center, its proper incline.

The carriage is fed forward until the blank is dressed across the back. It is then retracted and the shovel-blade removed from the machine completely finished, except the lower back edge, which is left thick. This is beveled off upon a frizzer or other shaping-machine. The guide L may be dispensed with by making a slot on the inside of guide K to receive a pin secured to the bed-plate.

It is evident that, instead of making the bed-plate B vertically adjustable to bring the shovel-blade up, the cutter-head may be mounted in adjustable bearing, so that it may be elevated and lowered for the same purpose.

Malt-shovels are now usually made with blade and handle in one piece, and as they are generally used upon cement or concrete floors the blade quickly wears out, while the handle is in perfect condition.

In Figs. 7 and 8 I have shown an improved detachable handle, by which improvement I am enabled to make the blades separately, thus effecting a great saving in material in the first instance and of labor and material after, as

when the blade is worn out it can be readily detached from the handle and a new one secured in place.

As I intend to make this improved shovel 5 the subject of a separate application, it will only be described here sufficiently to show how the blade is finished upon my machine.

The detachable handle is ferruled upon the end, the metal ferrule extending below the end 10 of the handle to form a socket to receive a short piece of handle formed with the blade. The end of this piece is turned down like the end of the handle to embed the ferrule. The end of the handle has a screw secured in its end 15 which extends beyond the ferrule. This is screwed into the piece of handle on the blade, drawing it within the ferrule and making a secure joint. To finish this kind of blades they are first sawed out to the proper size, the piece 20 of handle turned, and the shoulder or neck chucked to the exact size. The blank is secured upon the bed-plate B and the handle secured to it. By this the blade and plate B are turned as the front of the shovel is being dished 25 out by the cutter.

I claim—

1. The combination, substantially as before set forth, of the rotary cutter-head, the vertically-adjustable and sliding carriage, and the 30 bed-plate pivoted on top of the carriage and

adapted to be horizontally turned in either direction at pleasure.

2. The revolving cutters C C, in combination with bed-plate B, carriage D, frame E, slides G, treadle F, and feed-screw I, in a machine 35 of the character described, for the purpose specified.

3. In a shovel-forming machine, the bed or carriage J, in combination with curved guides, as K K' L, said guides being arched upon top 40 and curved upon their inner vertical edges, for the purpose set forth.

4. In combination, the carriage J, slotted guides L and K', said guide L being secured to the under side of the carriage in a position 45 to support and guide the carriage at that end upon a single pin, and said carriage having two pins upon the opposite side to enter the slot in guide K, the parts united and operating together in the manner hereinbefore set 50 forth.

5. The combination, substantially as specified, of carriage J and slotted lug O with screw M and follower N, pins n n', and slotted guide P.

JACOB FRANZMANN.
